[57] CLAIM

The ornamental design for a drumstick case, as shown and described.

DESCRIPTION

FIG. 1 is a top front perspective view of a drumstick case with the cover flap in closed position showing our new design;

FIG. 2 is a top front perspective view thereof, with the cover flap in an open position;

FIG. 3 is a top plan view of FIG. 1;

FIG. 4 is a bottom plan view thereof;

FIG. 5 is a left side elevational view thereof;

FIG. 6 is a front elevational view thereof;

FIG. 7 is a right side elevational view thereof; and,

FIG. 8 is a rear elevational view thereof.

FIG. 1

FIG. 2

FIG. 3
